CLAIM

The ornamental design for a wireless charger for mobile game device, as shown and described.

DESCRIPTION

FIG. 1 is a front left perspective view of a wireless charger for mobile game device showing my new design;

FIG. 2 is a front right rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the wireless charger for mobile gaming device that form no part of the claimed design.

The wireless charger for mobile gaming device is shown with a symbolic break in its length. The appearance of any portion of the article between the break lines forms no part of the claimed design.
